UNITED STATES PATENT OFFICE

2,634,313

LINE WIRE TRANSPOSITION BRACKET

Frederick G. Ridgers, Hamilton, Ontario, Canada,
assignor to N. Slater Company Limited, Hamilton, Ontario, Canada

Application April 21, 1951, Serial No. 222,186

1 Claim. (Cl. 174—33)

1

My invention relates to a transposition bracket for communication lines.

The principal object of the invention is to provide an improved transposition bracket, mainly in that it will better resist deformation than do other known brackets.

Another object of the invention is to provide a transposition bracket which will be as strong as, though lighter than other known brackets.

In the drawings, wherein is shown the preferred form of my invention,

Figure 1 is a top plan view;

Figure 2 is a side elevation of Figure 1;

Figure 3 is a section on line 3—3 in Figure 1;

Figure 4 is an end elevation of Figure 1;

Figure 5 is a perspective view; and,

Figure 6 is another perspective view showing the application of the bracket.

Referring now by numerals to the drawings, B shows the transposition bracket in general in Figures 5 and 6. The bracket is adapted to support four insulators S. As is well known, such a bracket is secured to a pole cross-arm C where two wires of a line are to be crossed over. So crossing the two wires is known as transposition.

Where the two wires cross, a certain minimum distance must be provided between them, and such selected distance must not be varied. The bracket must therefore be rigid, so that it will not be bent or deformed, as otherwise the selected horizontal spacing between the two wires or the clearance or distance between them where they cross, will vary with the variations in the line tension.

The clearance between the two wires, where they cross, is determined by the vertical position of the two insulators, to which one line W1 is attached, relatively to the vertical position of the other two insulators to which the other line W2 is attached. Accordingly, the practice has been to provide portions of the bracket so formed as to provide mounts or perches for the support of the pins, mounting the insulators, in their required relative elevations or levels.

The bracket B, aforesaid, is preferably formed from a substantially rectangular flat steel plate or blank 10 having a middle portion 11 preferably provided with a substantially central elongate aperture 12 to prevent excessive accumulation of snow. The plate is adapted to rest upon the cross-arm, to which it is secured by bolts through holes 13.

The diagonally opposite corners of the plate are formed with raised or stepped-up portions 15, while the other two corners are formed with lowered or stepped-down portions 16. Anchored to and vertically supported by these portions or pin mounts 15—16 are conventional metal pins P, holes 14 being provided to locate and receive the pins.

The portions 15 are stepped up by bending the

2

corresponding corners of the plate first upwardly as at 18, and then horizontally, that is, in a plane parallel with the plane of the plate. These riser portions or webs 18, by which the plate merges with the portions 16 and which are substantially ogee shaped in cross-section, in effect act as ribs tending to resist deformation of the bracket.

As is known, the resultant pull on any one pin is not at right angles to the cross-arm, nor parallel therewith, but an angle less than 90° to the cross-arm. This may be best explained by reference to Figure 1 wherein the line T1 and T2 represent the direction of the opposite pulls on the pin, and the line R the direction of the resultant stress (the angles a—a are equal), this stress being in a plane bearing an angle b to the general vertical plane of the web 18. While the portion 15, outwardly of the rib 18, tends to distort, the web on the other hand prevents any substantial distortion of either the portion 15 or the plate inwardly of the web.

The two lower portions or pin mounts 16 are formed by bending the plate downwardly as at 20, and then horizontally or in a plane parallel with the plane of the plate, the portion 20 also serving as a strengthening rib. Obviously, the explanation applying to the pin mounts 15 and webs 18 similarly applies to the stepped-down pin mounts 16 and webs 20.

The end edges defining the central aperture 12 are curled downwardly, in effect to provide a transverse rib 22 which serves to resist bending or deformation of the plate transversely of the longitudinal axis of the plate.

What I claim is:

A transposition bracket pressed from a substantially rectangular flat metal blank and comprising, a middle portion presenting a substantially flat face adapted to be laid upon a cross-arm, said middle portion having a substantially rectangular aperture, and substantially triangular shaped corner portions offset from the plane of said flat face and forming supports for insulator pins, those of said corner portions disposed diagonally opposite each other constituting pairs, each said pair lying on opposite sides of the plane of said flat face, and at least two of the edges defining the aperture being curled to provide ribs.
